ABSTRACT: A switching device for performing switching operations between a first group of incoming lines and a second group of outgoing lines in response to an input signal representing in a selected code the identification of an incoming and outgoing line is provided. The switching device includes a plurality of bistable input frames and a plurality of bistable output frames which are actuated in response to a coded input signal. The device also includes a plurality of bistable junction rods mounted for transverse movement relative to the bistable input and output frames which are also actuated in response to the input signal. The bistable input and output frames and the junction rods operate circuits associated with the bistable frames for selectively connecting incoming and outgoing lines connected to the circuits.

THREE DIMENSIONAL MATRIX FOR PERFORMING SWITCHING OPERATIONS

This invention relates to a switching device with automatically predetermined itineraries.

Numerous mechanical switching systems are already known, which may be divided into two categories. In the first, use is made of rotary switches, whilst the second comprises electromechanical devices having parts disposed orthogonally and operated by relays.

The invention relates more particularly to devices of the second category, in which connections are made in a space having two orthogonal dimensions. This arrangement results in one of the aforesaid parts being immobilized throughout the period when a connection is made. The capacity of the device is strictly dependent on the numerical quantity of the parts it contains and the dimensions and cost price of the device are directly proportional to the said quantity.

The present invention has the aim of providing a switching device with automatically predetermined itineraries which make it possible to define connection points and to make connections passing through said points in order to join an incoming line and an outgoing line in dependence on the arrival of messages or information, the connection points being defined in three-dimensional coordinates such that, when the connection is made and maintained, all the control elements become available again with the sole exception of the element making the connection.

For this purpose, the switching device comprising input elements and output elements connected respectively to an input and an output for messages or information is characterized in that it comprises:

at least three groups of all or nothing signal receiver input elements, each group being composed of as many input elements as there are signals addressed to said group;

at least three groups of selection elements having two stable states, in which each selection element is dependent on a predetermined input element;

at least one first set of elements having two stable states and controlling input connection points, in which the selection of a connection point control element is determined by all the elements of its selection group;

at least one second set of elements having two stable states and controlling output connection points, in which the selection of a connection point control element is determined by all the elements of its selection group;

and at least one third set of switching elements having two stable states, in which each element capable of cooperating with the first two sets of connection point control elements, belonging to a junction circuit with which it is associated, is also capable of cooperating with all the elements of each of the two aforesaid sets, and in which the selection of a switching elements is in addition determined by all the elements of its selection group, the states or positions of the various elements being fixed on each occasion in accordance with the code adopted and being able to be established by any electrical, pneumatic, hydraulic, or other suitable means, each of the elements of said set of switching elements being capable of marking the state of occupation of its own junction circuit, of controlling the simultaneous closure and maintenance of the junction made between the selected input point and output point, and finally of modifying the address of the junction circuit when said circuit is occupied, thus directing subsequent calls, normally intended for said junction circuit, to another junction circuit which is free.

The selector elements may advantageously be relays or multilayer semiconductor elements or mechanical elements, such as bars or strips. The selector elements may for example be of the type described in our prior U.S. application Ser. No. 678,658 filed on Oct. 27, 1967. The connection point control elements may be relays, multilayer semiconductors, rods, bars, or other means such as discs, moving dials, and so on, while the connector elements may also be of any known type.

The connection points of the connector elements may be carried by printed circuit plates.

The movements of the moving elements may be produced by electromagnets controlled by the information received direct or modified.

Referring to the case of telecommunication, the object of the invention can be explained as follows:

In a switch device automatically effecting all the switching operations between a first group of incoming lines composed of conductor wires and a second group of outgoing lines composed of conductor wires, by means of all or nothing signals applied to a series of electromechanical or electrical input elements, said signals representing in the selected code the identification numbers of the incoming line and of the outgoing line, each incoming information signal represents a binary number which is addressed to at least one predetermined element which is excited when said signal has the value 1, all the input elements constituting at least three groups, and each group of input elements selecting a connection point control element from a set. The number of elements of a set is determined by the number of different words which the total of the signals applied to the input control elements of the group can represent in the selected code. The selected elements effect simultaneously the selection and the control of the two connection points, these points being disposed in ordered rows, constituting a three-dimensional matrix.

Each row of connection points is divided into two subsets, the first of which is associated with the incoming lines and the second to the outgoing lines.

The connection points of the same row are connected:

30 1. To a common junction circuit;
2. To the line to which they belong.
The association of a line with a subset of connection points of a row, which are connected to a common junction circuit, is determined by the portion of its coded number corresponding to the series of binary signals addressed to the input elements of the signals of the group which selects the single control element of this same junction circuit.

40 The ordinal position of a line in a subset of connection points of a row which are connected to a common junction circuit is determined by the portion of its coded number corresponding to the series of binary signals addressed to the input elements of the group which selects the single element controlling the selection of a line simultaneously in each row, a connection point of an incoming line and a connection point of an outgoing line being thus selected in each row.

45 When the selector elements are of the type described in the aforesaid Patent application, there are provided at least three groups of input electromagnets:

50 a first group controlling the positioning of a series of bistable (input) frames determines the choice of a single one of these frames, which through its displacement prepares the control of the contacts of all the connection points situated in its plane and belonging to the incoming lines, each of these connection points being connected to a different junction circuit;

55 a second group controlling the positioning of a series of bistable (output) frames determines the selection of a single one of these frames which, through its displacement, prepares the control of the contacts of all the connection points situated in its plane and belonging to the outgoing lines, each of these connection points being connected to a different junction circuit;

60 a third group controlling the positioning of a series of bistable junction rods, the displacement of which transversely to that of the aforesaid frames controls, together with the two frames selected which are then in the active position, the contacts of the two connection points; when the connection has been made the frames are returned to the position of rest and 65 they are available again, each junction rod being held in the active position throughout the duration of the connection.

70 When any of the incoming lines must be able to be connected to any of the outgoing lines, where the connections are made in any order and where the number of connections 75 maintained simultaneously may be equal to the number of

junction rods, the number of junction rods is multiplied and either the junction frames of the incoming lines or the junction frames of the outgoing lines are multiplied in order to constitute a plurality of groups.

The occupation of a junction circuit, having the material result that a junction rod of a group is in the active position, prevents any other connection to the circuit, so that the junction rod transfers to another circuit the function of making connections intended for that circuit.

In one form of construction of the device, the distribution of the connection points in the first group differs from the distribution of the connection points in the second group and all the connections which can be made with the aid of a junction circuit of the first group are distributed in the second group to an equal number of separate junction circuits, and vice versa.

The invention is described in greater detail below with reference to the accompanying drawings, in which:

FIG. 1 illustrates diagrammatically the layout of the switching device in a telephone exchange for operating with dial calling.

FIG. 2 illustrates diagrammatically a switch according to the invention.

FIG. 3 illustrates diagrammatically the method of making circuits between connection points distributed in a three-dimensional space.

FIG. 4 illustrates in plan and in section along the line IV—IV in FIG. 6 a form of construction of some switching elements, viewed at the end of the first so-called selection half-period.

FIG. 5 is a section along the line V—V in FIG. 4.

FIG. 6 is a section along the line VI—VI in FIG. 4.

FIG. 7 is a similar section to FIG. 6, but the switching elements are shown at the end of the second (so-called switching) half-period in the making of a circuit.

FIG. 8 shows a form of construction of the junction frame selection device.

FIG. 9 shows diagrammatically the other levels of a small 24-line telephone switch.

FIGS. 9₁—9₅ illustrate diagrammatically the operation of the telephone switch of FIG. 9 in completing connections between selected calling and called lines.

FIG. 10 shows the automatic making of the itineraries, which corresponds to twofold multiplying.

FIGS. 10_a—10_b illustrate the automatic routing of telephone calls in the switching device of this invention which correspond to the connections between selected calling and called lines shown in FIGS. 9₁—9₅.

FIG. 11 illustrates diagrammatically an example of tenfold multiplying.

FIGS. 12₁—12₆ illustrate the operation of the switching device on messages identifying selected calling lines and called lines to identify the combination of elements in the switching device to be operated to complete connections between the selected lines.

Although the switching device of the present invention is applicable to all remote control systems or to the most diverse programming, for the purpose of explanation, its application to an electromechanical form of telecommunication is described below.

A switch for making connections between telecommunication lines is designed to operate in two integrated stages and to effect all the possible connections between a first set of incoming lines and a second set of outgoing lines. The connections are made either between a plurality of switches of a first telecommunication exchange or through the cooperation of said exchange with other transit and/or terminal exchanges.

FIG. 1 illustrates diagrammatically the layout of said switch in an exchange for operating with dial calls originating from subscriber's stations. All the subscriber's calls connected to this exchange arrive at the switch A-C, the numbers being represented in a binary coded decimal notation.

The switch is controlled by the binary-decimal code of the numbers of the calling line and of the called line. A coded message simultaneously and automatically determines:

1. the junction circuit;
2. the point of connection of the calling number;
3. the point of connection of the called number, by instantaneously effecting the closing of two multiple contacts (for example with triple contacts, two are for the lines and the third is for testing) to make the desired connection.

The circuit thus made is held. However, the switch is also capable of carrying out other switching operations, at a rate of several operations per second. A switching operation either makes a circuit or interrupts a circuit previously made, for example, when a call on an occupied line finishes. When a plurality of lines are grouped under the same number (same prefix, service or subscriber having a plurality of lines), the switch makes the connection to one of the free lines without any search and without any additional information. A switch of this type is capable of functioning with all suitable subscriber's telephone sets.

In all the examples described herein, the code adopted is the 8421 code, but the switch is capable of operating with any other codes (for example with the codes used on pushbutton-type instruments already in existence).

The switch operating message can in addition be transmitted direct in the four-element code by a suitable subscriber's set, thus making it unnecessary to use a code converter upstream of the switch.

In FIG. 1, communication from a subscriber's set A is made through the switch A-C. When making a call, the caller A directly operates a supply relay ReL, which in turn energizes the relay Re1. The relay Re1 makes circuits in the switch A-C by means of contacts, which represent the caller's number in a unique code.

For example, taking the binary coded decimal of the number 37, i.e. 11-0111, then relay Re1 corresponds to number 7 in a set of number 3. Similarly, the number 38, i.e. 11-1000 occurs when relay Re1' corresponds to number 8 in the same set of number 3.

The relay ReL and Re1 are connected by the wires 2 and 3 to the group recorder Eg, which records the trains of pulses transmitted by the subscriber, and may be also designed to include a decimal to binary code converter. The encoded signals are transmitted to the switch A-C by connecting circuits 4.

The subscriber's circuits are divided into groups. If it is assumed that the switch A-C comprises 800 junction circuits, and is capable of effecting switching between 1200 subscribers A of an exchange, and 400 outgoing lines B, the particular feature of the arrangement is that it can simultaneously effect the 400 possible junctions.

In addition, if each set comprises 40 subscribers and is served by two group recorders Eg (multiplying with displacement by 20), the total of the code numbers is defined, as a maximum, by five contacts in each relay Re 1, Re 2...Re n.

In fact, from 0 to 39, the information encoded into 8421 binary-coded decimal will go from 00/0000 to 11/1001. There are found per decade a maximum of three bits having the value 1, and the relay does not need contacts to represent bits of the value 0. The portion of the number which relates to the group is handled by the contacts of the common recorder of the group.

A group recorder carries as a maximum three contacts: two for the decimal positions, thousands, and hundreds up to 1199; since neither the thousands nor the hundreds can have any other value than 0 or 1, one contact is sufficient for the tens (for the signals of positions 8 and 4), the other signals being already defined by the relay 1.

Details of the distribution of the signals are given because the same principles are applied to the treatment of all the information. Nevertheless, this explanation does not contain a description of the circuits which, without selectors or other additional apparatus, effect the recording of the signals without overlap when calls in the group coincide.

The arrangement of the circuits in the switch of the example corresponds to the following conditions:

1. The number of junction circuits J is an even number (this condition being necessary for the formation of the two groups) and $J/2$ is a multiple of a number N close to $\sqrt{J/2}$. In addition $J/2=M \times N$, because of the condition determined by the three-dimensional arrangement, M and N being two whole numbers, M representing the number of junction circuits per circuit plate and N the number of plates.

Thus, in the example considered for $J=800$ and $J/2=400$ we have $N=M=\sqrt{J/2}=20$.

2. The coded information is treated as two separate words, one representing the number N and the other the number M to comply with the condition permitting direct control and notation in code such as to correspond to a continuous decimal notation. By "word" must be understood a certain constant number of binary signals.

Thus in the preceding example, if B represents a set of 400 outgoing lines, its representation in the code (8421) adopted will consist of two words of five bits placed end to end, B being composed of a certain number of subsets, and the first word will identify one of these subsets, and the second a term in each subset.

FIG. 2 shows the routing of the message M_e transmitted to the switch. This message M_e is composed of two terms:

- a. the coded number of the calling line A : I_A ,
- b. the coded number of the called line B : I_B .

Each of these two terms is composed of two "words."

The signals making up the first word σ_1 of the information I_A are addressed simultaneously to a group of electromagnets E_{SA} , each signal operating a separate electromagnet of the group.

The signals making up the second word σ_2 of the information I_A are addressed simultaneously to a group of electromagnets E_{CA} , each signal operating a separate electromagnet of the group.

The signals making up the first word σ'_1 of the information I_B are addressed simultaneously, on the one hand to a group of electromagnets E_{CB} (first group), and on the other hand to a group of electromagnets E_{SB} (second group), each signal controlling a separate electromagnet of the group.

The signals making up the second word σ'_2 of the information I_B are addressed simultaneously on the one hand to a group of electromagnets E_{CB} (second group), and on the other hand to a group of electromagnets E_{SB} (first group), each signal controlling a separate electromagnet of the group.

The electromagnet of the group EG which controls the selection of the group is operated by the reception of a signal transmitted by the switch, this binary signal being dependent on the one hand on the present state of the connections established and on the other hand on the message.

Each of the aforesaid electromagnets controls the positioning of a selection means capable of occupying two stable positions.

FIG. 3 illustrates diagrammatically an arrangement which permits the making of the circuits between connection points distributed in a three-dimensional space, defined by the planes xoz , zoy and xoy . Three horizontal rods T_1 , T_2 , T_3 , are situated in the plane zoy and three other rods T_5 , T_6 , T_7 are situated in a plane parallel to zoy . These rods, known as junction rods, can each occupy two stable positions by movement along their longitudinal axis.

Fixed vertical bars A_1 , A_2 , A_3 , A_4 carrying contacts a , each of which represents an incoming line of a set of lines A , are situated in two parallel planes xoz .

Horizontal bars B_1 , B_3 , B_5 , B_2 , B_4 , B_6 at right-angles to the previously mentioned rods T carry contacts b , each bar representing one of the lines of a set of lines B .

In order to make a junction between a line A and a line B , there is defined a plane of contacts a parallel to the plane xoz in the group A , and a second plane of contacts b parallel to the same plane in the group B . Frames CA_0 , CA_1 , and CB_0 , CB_1 , (not shown) move in the direction of the arrows which represent them symbolically, so as to assume one or the other

of the two positions permitted to them. The frame CA_0 selects the plane of the contacts mounted on the vertical bars A_1 , A_3 ... and the frame CA_1 selects the plane of the contacts mounted on the vertical bars A_2 , A_4 ... The frame CB_0 carries all the horizontal bars B_1 , B_3 , B_5 and the frame CB_1 carries all the horizontal bars B_2 , B_4 , B_6 ....

If it is desired to make the connection between a calling line A identified by A_2 and a called line B identified by B_6 , these identifications become 01 and 101 respectively in the binary system. The figure 1 of 01 defines the frame CA_1 , which will prepare the closing of all the contacts a situated in its plane. Similarly, the unit figure of the information B 101 will define the frame CB_1 , which will prepare the closing of all the contacts b situated in its plane.

15 The junction rod identified by the remainder of the message, that is to say 010, which is the code number of the rod T_3 , will then be displaced in the direction of the arrow, which will have the effect of closing the contacts situated on its path and which have been prepared by the displacement of the two frames CA_1 and CB_1 , thus making the connection between the line $A_2=2$ and the line $B_6=6$.

It will be observed that through its displacement the frame CA_1 will have simultaneously prepared all the contacts a of the vertical bars A_2 , A_4 ..., while the frame CB_1 will likewise have prepared all the contacts b of the horizontal bars B_2 , B_4 , B_6 ... to cooperate with all the rods T . But since only the rod T_3 is operated, such cooperation will take place only with said rod, and it will be only the contacts a and b enclosed in a dotted circle which will close the circuit.

20 From the foregoing and by referring again to FIG. 2, it will thus be seen that each of the following sets of selection means selects as follows:

- a. S.C.A.: one movable junction frame C.A.;
  - b. Sel-A: two sets of the same number of junction rods T , each set belonging to a separate group 1 or 2;
  - c. Sel-B, first group: a set of junction rods T belonging to the group 1;
  - d. Sel-B, second group: a set of junction rods T belonging to the group 2;
  - e. S.C.B., first group: a movable frame Cb of the first group;
  - f. S.C.B., second group: a movable frame $C.B.$ of the second group;
- and the selector Sel-G selects the group of junction rods T_1 or 2.

25 It should be noted that the three sets Sel-A, Sel-B of the first group and Sel-B of the second group and the selector Sel-G thus determine the single junction rod T the choice of which is dependent on the one hand on the message and on the other hand on the connections already made at the moment of the reception of the message.

30 The connection between the line A and the line B is made firstly by the intersection of the selected frame C.A. and rod T , determining the first connection point belonging to the line A and to a junction circuit, and secondly by the intersection of the frame C.B. of the same group as the rod T with the same selected rod T , thus determining the second connection point belonging to the line B and to the same junction circuit.

35 It is seen that the form of selection and space which has just been described requires only a minimum of signals, all of which are included in the message composed only of the calling number and the called number.

EXAMPLE:

If we consider:

- a. the lines of the set A (FIG. 3) coded in binary:

1=00	3=10
2=01	4=11

- b. the lines of the set B coded identically:

1=000	4=011
2=001	5=100
3=010	6=101

and

c. the rods T:

1=000	5=100
2=001	6=101
3=010	7=110
4=011	

The plane xoz of the set of lines A is determined by the "unit" signal of the binary information relating to the line A.

The plane xoz of the set of lines B is determined by the "unit" signal of the binary information relating to the line B.

The other signals of A and B designate the rod T which will be selected.

Let the message be A=2 and B=6. In code this will become A=01 and B=101, and the selection will be as follows:

CA=1 and CB=1   01   101
 ↓   ↓   ↓
 selected rod   0 — 10 — T₃(010)

FIGS. 4 to 7 illustrate a form of construction of the selection and switching elements of the switch.

The present invention provides a switching device for performing switching operations between a first group of incoming lines and a second group of outgoing lines in response to an input signal representing in a selected code the identification of an incoming and outgoing line. In a preferred embodiment of the invention, a switching device for selectively operating a plurality of circuits includes first and second cards for supporting the circuits. Each card has a plurality of projecting elastic blades for making electrical connections to the circuits located on the cards when the blades are moved into contact with the circuits.

A crossed bar switch of this type is composed of a series of superimposed levels N, each level being constituted by the space contained between two horizontal cards I M1 and I M1', (FIGS. 5 and 6) carrying printed circuits which are fixed in relation to the frame and also carrying elastic blades 11 capable of effecting the closing of the circuits, as will be described later on.

FIG. 5 shows only a part of the first level N1 of the switch, but the same arrangement is adopted for all the other levels.

Between the cards I M1 and I M1' there are disposed horizontal junction or selection rods T capable of occupying two positions which, in order to locate them accurately in the entire device, are indicated by T₁¹ and by T₁², the bottom index indicating the level in which they are situated and the top index indicating the numbering in the same level.

In the junction rods T there are formed notches or slots 12 each of which is adapted to receive a ball R, the balls being accommodated, when the device is at rest, in sockets 13 formed in bars P1, P2 fixed on the frame carrying elastic tongues 14 insulated from the contacts.

The junction rods T are adapted to slide along their longitudinal axis between the bars P.

On each side of the bars P and of the junction rods T there are disposed plates CA1, CA2, CA3, CA4... situated horizontally and transversely in relation to said rods and bars.

In accordance with the invention a plurality of bistable input frames mounted for transverse movement relative to the cards is provided. The bistable input frames are movable from first inoperative positions to second operative positions and each of the bistable input frames has a plurality of notches.

The plates CA1, CA2, CA3, CA4... (FIGS. 4 and 5) are fixed at both ends on uprights M1, M2, M3... respectively associated with them and thus forming frames having horizontal transversal partitions, which will be called junction frames CA hereinbelow, together with the index designating their position.

The plates CA1, CA2, CA3, CA4... (FIGS. 4 and 6) are provided with semicircular notches 15 each of which is able to receive a ball R and is extended by an inclined nose 16 cooperating with stops 17 fixed on the bars B in order to pass

the balls R contained in the sockets 13 in said plates into the notches 12 of the junction rods T, this movement of translation being effected by a sliding movement of each frame CA at right-angles in relation to the possible sliding of the junction rods T crossing it; a similar arrangement is made for the frames B, so that each frame can thus select as many balls R as there are junction rods crossing it and belonging to the same group of frames.

In accordance with the invention means are provided for selectively moving one of the bistable input frames from its inoperative position to its operative position to move the balls located in the notches formed in the bistable frame into the slots of the selection rods located adjacent to those notches. As mentioned above, a group of electromagnets ECA (FIG. 2) is provided for operating selection means SCA to move one of the frames CA to its operative position.

Further, in accordance with the invention means are provided for selectively moving one of the selection rods from its first position to its second position to move the ball located in one of its slots into an operating relationship with one of the blades projecting from the card to bend that blade into contact with the corresponding circuit on the cards. Referring to FIG. 2, junction or selection rods T are selectively operated in response to a set of signals derived from message Me. As mentioned above, a group of electromagnets ESA is provided which is operated by the first word σ_1 of the information IA.

The electromagnets of this group operate a selection means Sel-A for the junction rods T. 47 In addition, a group of electromagnets ECB (1st group) and a group of electromagnets ESB (2nd group) are provided which operate in response to word σ_2 of information IB of message Me. These groups of electromagnets operate through selection means SCB (1st group) and Sel-B (2nd group), respectively, to select the junction rod T that is operated.

Alternatively, a group of electromagnets ECB (2nd group) and a group of electromagnets ESB (1st group) can be operated in response to a word σ_2^1 of information IB of message Me. These groups operate through selection means SCB (2nd group) and Sel-B (1st group), respectively, to select the junction rod T that is operated.

The operation is as follows:

When a frame CA is in the position of rest, it holds the balls R by means of its notches 15 against a bar P. For example, it is seen in FIGS. 4 and 6 that the frames CA1 and CA2 hold the balls R₁¹, R₁², R₂¹, and R₂² in the operative position against the bars P1 and P2 and out of the path of the selection rods T₁¹ and T₁².

As soon as a frame—only one frame per group—is selected, it is moved by its electromagnet S.C.A. in the direction of the arrow f (FIG. 4); for example, if the frame CA3 is considered, it is seen that said frame has been operated and that it is holding the balls R₃¹ and R₃² in the operative position. In this position said balls are in the notches 12 in the junction rods T₁¹ and T₁².

The switching half-period consists of a longitudinal displacement of the junction rods, T selected by the selection plates Sel-A, Sel-B, and Sel-G (FIG. 2).

In FIG. 7 it is seen that the junction rod T₁² is displaced and that it carries with it the ball R₃² (the only ball situated at the intersection of the plate CA3 and said junction rod T₁²).

The guide stops 17 and elastic tongues 14 effect the guiding of the balls R into all their positions. When a ball is displaced, like the aforesaid ball R₃², the tongue 14 fixed on the bar P₃² is deformed by that ball alone and is pressed against the contact blade 11, which closes the corresponding printed circuit on the card IM'1.

It will immediately be observed that the cards IM can easily be made removable, so that on the one hand they can be easily repaired or replaced, and on the other hand they can easily be exchanged without it being necessary to dismantle any part of the switch.

FIG. 8 illustrates a form of execution of the control and selection of the junction frames CA, CB of the first group and

CB of the second group; in the example illustrated, three frames C2, C3, C4 are in the inoperative position (that is to say they do not participate in the selection of the connection points). Only the frame C1 has been displaced under the action of the return spring 18a so as to assume an operative position, this displacement being permitted if the two following conditions are complied with:

- The shaft 19 carrying the arm 20 equipped with rollers 21 acting on stops 22 carried by the frames frees all the frames by rotating through $\pi/2$ in order to reach the position shown in the figure;
- Neither of the two selection bars SC1 and SC2 has any stop projection preventing the displacement of the frame acted on by its own spring. In the FIGURE these bars are in the position 0 and the frame C1, identified by the binary number 00, is the only one complying with this condition.

Each bar SC1 and SC2 which is adapted to move in the direction of the arrows "f" is operated by an electromagnet (not illustrated) determining its position 0 or 1 in dependence on the signal received, their displacement being limited by fixed pins 23 in their two positions 0 and 1.

The two bars have thus selected one of the four frames the displacement of which selects a connection point, and then the shaft 19 turns by $\pi/2$, which has the effect of bringing back to the inoperative position the only frame which was displaced, and then of maintaining all the frames in that position, freeing the selection bars, which are again available. Thus in order to control n frames it is sufficient to have a number of selection bars equal to the number of binary signals required to represent n in the code used.

FIG. 9 shows four tables, each of which illustrates one of the four levels of a small switch described by way of example and comprising eight lines A numbered from 0 to 7 and 16 lines B numbered from 0 to 15.

Each table represents the connection points of a card IM and of a card IM'. The divisions represent the connection points and the numbers shown therein are the numbers of the lines connected to the contacts of said connection points. In each division the numbers are written in decimal form with their coded representation.

In order to facilitate the explanation of the multiplying and grouping of the lines under the same call number, the numbers 4, 8, and 13 have been eliminated. There are thus available four lines B grouped under the number (0₀, 0₁, 0₂, 0₃) and three lines B grouped under the number 9 (9₀, 9₁, 9₂). Each frame is represented diagrammatically by a horizontal arrow line. Each junction line is represented diagrammatically by a vertical arrow line.

At the end of each arrow the binary number permitting its identification, and consequently its control, is indicated.

It will be seen below how the different signals for the identification and control of the rods and junction frames are distributed; in the example selected each junction rod of the first and second groups is identified by a binary information composed of four signals permitting its selection.

Each junction frame CA and CB is identified by a binary information composed of two signals permitting its selection.

It will also be seen below how the message composed of the binary signals representing the number of the calling line and that of the called line bring about, in dependence on the state of occupation of the switch, the control and selection of all the elements: rods, frames, and junction circuits.

The Table below illustrates how the different signals are distributed.

Table -Continued

Second group junction rod	occupation	2° A	1° B	2° B
5 Frame CA		3° A	4° A	
Frame CB, 1st group		1° B	2° B	
10 Frame CB, Second group		3° B	4° B	

On the first line of the Table it is seen that the four signals for identification and control of the rods of the first group are successively and in order as follows:

- a signal dependent on the state of occupation of the lines;
- a signal which has the value of the second figure of the coded number of A;
- a signal which has the value of the third figure of the coded number of B;
- a signal the value of which is that of the fourth figure of the coded number of B.

In the following lines of the Table it can similarly be seen how the identification signals are distributed:

- for the selection rods T of the second group (4 signals);
- for the junction frames CA (2 signals);
- for the frames CB, first group (2 signals);
- for the frames CB, second group (2 signals).

A junction rod, first selected and then operated, makes the connection between the junction rods own junction circuit and the two contacts selected by a frame CA and a frame CB (FIG. 9).

The first signal of the information noted (below the line representing the junction rod to be selected) is addressed to the electromagnet EG (FIGS. 2 and 10). This electromagnet is energized when the value of the signal is 1. The electromagnet EG controls the displacement of the selection plate Sel-G (FIG. 2). When the latter is in the position of rest (value of the first signal equals 0), the junction rods T belonging to the first group are free and the junction rods T of the second group are locked.

When the selection plate Sel-G is displaced through the action of the electromagnet EG, all the junction rods T of the first group are locked and those of the second group are free.

The source of this first signal will be explained during the description relating to FIG. 10.

A selection plate Sel-A (FIG. 2) is controlled by the electromagnet ESA energized by the second signal of the number of line A. The first signals of the information corresponding to the call number of the lines A all having the value 0, they are not taken into account (8 lines numbered from 0000 to 0111).

Internal multiplying with displacement is effected in the following manner.

The call numbers of the first group A are found again in the same order at the corresponding level of the second group A.

The same call numbers are likewise found again for the ungrouped lines of B in the two groups with a modified arrangement, one subseries of numbers B of the first group belonging to a same junction circuit is distributed, in the second group, in such a manner that all the numbers of this subset are each served by a different junction circuit. A subset of contacts controlled by a common junction rod of the first group corresponds to a second subset of contacts connected to the same incoming lines B in the second group, which are selected by a common frame CB of the second group, and vice versa.

A frame CA or CB is immediately free after switching has been effected, and it is ready to participate in further switching. This is not the case for the junction rods, which are locked throughout the duration of the connection. They return to the free position only on the interruption of the communication (the junction rods thus represent the marking and memory elements of the switch).

Identity 1°σ Element	2°σ	3°σ	4°σ
First group junction rod	occupation	2° A	3° B

Through the "generalized displacement" explained above, the internal multiplying eliminates the random variable of the probability of the junctions.

In fact, without internal multiplying (using only the first group) a communication A_1-B_6 would prohibit a second junction A_2-B_2 etc., that is to say all the communications which would have to utilize the same junction circuit. With the internal multiplying all the connections between the unoccupied accesses are simultaneously possible.

The passing of a call from the first to the second group is shown in FIG. 10.

In this figure, the first row on contacts comprises the contacts operated by the junction rods T of the first group, and the second row shows the contacts operated by the frames CB of the second group, the third row showing the contacts operated by the junction rods T of the second group.

In the operation of the switching device, all of the control operations to close, maintain or break the switching line, i.e., the multiple selection control, the marking of the paths and the routing of the call via free junction circuits, are integrated and entirely disposed in the switching device thereby eliminating the need for specialized peripheral apparatus. The operation starts with only the information which is communicated to the switching device in the message Me composed only and without any repetition of the code number of the incoming line (A) and the code number of the outgoing line (B). A part of the information contained in the message may be transformed by the occupied state of the junction circuits.

The information bits IA and IB of message Me define the input and output lines as well as a priority routing in the switching device. A portion of the signals contained in the information bits whose ordinal position determines the address or addresses is used twice: first, to define the access of the lines, and second, to define the junction circuit or circuits.

In order to simplify the operation, it will be assumed that the junctions of the first group have priority. The electromagnet EG is not energized. Only the junction rods controlled in dependence on the information the first signals of which are 0 participate in the switching if they are in the inoperative position, that is to say if they are free.

When the priority junction circuit designated by the message is free, the information contained in the message is not transformed. On the other hand, a portion of the information is automatically transformed when the junction circuit or circuits designated by the initial message are occupied. The modification of the information is effected by the closing or breaking of each communication by changing the state of the junction element (T) which is, moreover, in the switching circuit, the memory element of the communication thus established.

Each of the junction rods T of the first group closes a contact when in the operative position. All of the closed contacts (left-hand column in FIG. 10) represents all of the occupied junction circuits of the first group at a given moment. When a new call arrives for which the junction circuit is occupied, the preselection of the corresponding frame CB of the second group represents this new message. In each level assigned to a subset of the first group each frame controls the closing of a contact. The circuit made by the contacts in series represents the value 1 of the first signal of the information defining the selected junction rod (first and second columns of FIG. 10). This signal 1 addressed to the electromagnet EG, representing the first signal defining the junction rod, controls the group selection.

This new disposition of the junction elements provides, for each subsequent call, a possible transformation of a portion of the information contained in the next message. The address of each signal belonging to an information bit, whether modified or not, is univocal and is always characterized by its ordinal position. This possibility is a function of the state of the occupation of the junction circuit designated by the information contained in the initial message. This state of occupation is effected by the state of each junction element (T).

FIRST EXAMPLE

As explained above, FIG. 9 shows the four levels of a small switching device described by way of example which comprises eight lines A numbered 0-7 and 16 lines B numbered 0-15. The two tables of the first group illustrate levels 1 and 2 of the first group, and the two tables of the second group illustrate levels 1 and 2 of the second group.

The level of operation of the switching device is selected in this simple example by the second signal of the word $\sigma 1$ in information bit IA. This signal controls the operation of electromagnet ESA which, in turn, controls the selection plate Sel-A (FIG. 2). When the second signal of the information bit IA has a value 1, the level 2 is selected. In the opposite case, the level 1 is selected. In this simple example, the group of electromagnets ESA can be reduced to a single electromagnet.

In the following operation, it is assumed that all junction circuits are free (unoccupied) when a first call A_3-B_6 is initiated. The message $Me = IA+IB$ (FIG. 12₁) corresponding to the call A_3-B_6 will be 00110110 according to the selected code. This message represents the number of the calling line (A_3) followed by the number of the called line (B_6).

FIG. 12₁ shows how the signals comprising the message are univocally grouped and addressed to determine the operation of the switching device for the first half-period. The signals of the message Me select the following frames to be operated:

1. CA 11 ($\sigma 2$).
2. CB 1st Group 01 ($\sigma 1$).
3. CB 2nd Group 10 ($\sigma 2$).

FIG. 9₁ shows that frame CA defining the combination of the connection points of the lines A_3 and A_7 in the four level arrangement of the switching device is moved from its first position to its second position. It should be noted that the two binary figures (11) which constitute the word $\sigma 2$ correspond to calling lines A_3 and A_7 located in the first and second levels, respectively, of the switching device.

The frame CB 1st group defining the combination of the connection points for lines B_5 , B_6 and B_7 of the 1st group is identified by the two binary figures (01) which constitute the word $\sigma 1$ and is moved from its first position to its second position. The frame CB 2nd group defining the combination of connection points for lines B_2 , B_6 , B_{10} , B_{14} of the 2nd group is also identified by the two binary figures (01) which constitute the word $\sigma 2$ and is moved from its first position to its second position.

First half-period (FIG. 10₁a)

Since all junction circuits are initially free, the contacts in the signalling circuit (1st column) are open and the electromagnet for selection of an alternate junction circuit remains unenergized. Thus, the junction rod of the first group identified by $\sigma 1$ and $\sigma 2$, i.e., 0010, is selected.

Second half-period (FIG. 10₁b)

During the second half-period, the selected junction rod 0010 of the first group is operated, as shown in FIG. 9₁, establishing with the frame CA 11 and CB 1st group the connection of the lines A_3 and B_6 . In changing its state, the junction rod 0010 closes the contact of the same number (1st column of FIG. 10₁b). This contact will remain closed as long as the communication A_3-B_6 is maintained. As shown in FIG. 10₁b, the signalling circuit remains open at this time.

Once the communication B_6-A_3 has been established it is memorized by the operative position of the junction rod 0010 (FIG. 9). The corresponding contact (shown open in FIG. 10) will be closed during the communication, and then the calling by A_0 of the line B_{14} selects the junction frame CB 2nd G₁₀, thus through the closing of the circuit effecting the energization of the electromagnet EG. The new junction is thus controlled by the action of the junction rod 1011.

The subsequent call A_0-B_{14} is automatically oriented toward a free junction circuit. Referring to FIG. 12₂, the message Me corresponding to the call A_0-B_{14} will be 00001110. The signals

of this message select the following frames of the switching device to be operated:

1. CA 00 designating the connection points A₀ (first level) and A₄ (second level).
2. CB 1st group 11 designating the connection points B₁₂, B₁₄, and B₁₅.
3. CB 2nd group 10 designating the connection points B₂, B₆, B₁₀, and B₁₄.

The frames CA 00, CB 1st group 11, and CB 2nd group 10 are thus moved from their first positions to their second positions in the switching device.

First half-period (FIG. 10_{2a})

During the first half-period, the frame CB 2nd group 10 closes the two contacts 10 2nd column of FIG. 10_{2a}), and current is conducted through the contacts 0010 (1st column) and 10 (2nd column). The electromagnet EG is thus energized to represent a binary 1 (FIG. 12₂).

Second half-period (FIG. 10_{2b})

Since electromagnet EG is energized, the information ($\sigma 1$) which initially has a value 00 is transformed into the signals 10. As shown in FIG. 9₂, the junction rod and junction circuit 1011 of the second group are selected. This junction rod establishes with the frames CA 00 and CB 2nd group 10 the call A₀–B₁₄.

SECOND EXAMPLE

The same principles are applied to the selection of the grouped lines (PBX) on the same call number. Assuming that the communication A₁–B₀ is to be established, the message Me corresponding to this call, i.e., 00010000 (FIG. 12₃) is applied to the switching device.

First half-period (FIG. 10_{3a})

This message Me selects the following frames of the switching device to be operated:

1. CA 01 defining the connection points A₁ (first level) and A₅ (second level).
2. CB 1st group 00 defining the connection points B₀, B₁, B₂, and B₃.
3. CB 2nd group 00 defining the connection points B₀, B₂, B₃, and B₁₂.

Referring to FIG. 10_{3a}, when frame CB 00 of the second group closes both contacts 00 of the second column, the contact 0000 (first column) being open, the electromagnet EG is not energized. Thus, as shown in FIG. 12₃, the rod and the junction circuit T 0000 are selected.

Second half-period (FIG. 10_{3b})

The signalling circuit being open, the rod T 0000 is operated and controls the two connection points A₁ and B₀ (FIG. 9₃). In its operative position, the junction rod T 0000 closes the corresponding contact (1st column of FIG. 10_{3b}) in the 2nd half-period.

A subsequent call, e.g. A₀–B₀ (FIG. 12₄) identified by the message 00000000 will be oriented towards the second group in the following manner:

First half-period (FIG. 10_{4a})

The message Me (FIG. 12₄) identifies frame CA 00 which defines the points A₁ in the first level (FIG. 9₄), the junction circuit 0000 which is already occupied, and the frame CB 00 of the 2nd group. The frames CA 00 and CB 00 2nd group are moved from their first positions to their second positions in the switching device. The movement of frame CB 00 (2nd group) closes both contacts 00 (2nd column of FIG. 10_{4a}).

Since contact 0000 (1st column of FIG. 10_{4a}) is closed by the occupied junction rod, the electromagnet EG is energized to produce a binary 1 signal. As shown in FIG. 12₄, this signal transforms the word $\sigma 1$ into 10, the free junction circuit of the second group designated by 1000 is selected.

Second half-period (FIG. 10_{4b})

During the second half-period, the operation of junction rod 1000 of the 2nd group controls the two connection points of the switching device to establish the call A₀–B₀. The signalling circuit (FIG. 10) is open and the junction rod closes contact 1000 (3rd column of FIG. 10_{4b}) which prepares the orientation of the subsequent call.

Assuming that the two previous communications A₁–B₀ and A₀–B₀ are maintained when another call to line B₀ is effected at the same level, for example, A₂–B₀, the following operation occurs.

First half-period (FIG. 10_{5a})

15 The message Me 00100000 (FIG. 12₅) identifies calling line A₂ and called line B₀.

This message also identifies frame CA 10 which defines the connection points A₂ (first level) and A₆ (second level), the junction circuit 0000 which is already occupied, and the frame CB 00 of the second group. The frames CA 10 and CB 00 (2nd group) are moved from their first positions to their second positions in the switching device. The movement of frame CB 00 (2nd group) closes both contacts 00 (2nd column of FIG. 10_{5a}).

25 Since contacts 0000 (1st column of FIG. 10_{5a}) are closed by the occupied junction rod, the electromagnets EG and ESB1 are energized to transform the word $\sigma 1$ of the message to 10 and the word $\sigma'1$ to 01. As shown in FIG. 12₅, the free junction rod and circuit of the second group designated by the signal 1001 are selected.

Second half-period (FIG. 10_{5b})

35 During the second half-period, the contact 1001 (3rd column, FIG. 10_{5b}) will be operated to prepare the switching device for the last possible call at the first level, i.e., A₃–B₀. This call is identified by the message 00110000 (FIG. 12₆) and will be transformed by the switching device to 10111000. The electromagnets EG and ESB2 (FIG. 10_{5b}) will be energized designating the last free junction circuit for B₀ at this level, i.e., 1010.

45 When the number already occupies the junction circuit of the first group, for example when A₁ calls B₀, thus bringing about the junction 0001–0000 and consequently the occupation of the line B₀, the next number 0 call (for example: A₀B₀) will be made by the second group, as for the nongrouped lines. In the case of the grouped numbers, the contact of the second group is connected to a second line: 0 1.

50 The junction rods of the second group controlling one or more contacts of grouped lines operate, in their operative position, contacts shown in the third column in FIG. 10. The closing of the contact 1000 (the situation illustrated in FIG. 10) effects a second modification of the original call number through the excitation of the electromagnet ESB₁. The following call of B₀ will become 1011–0001 instead of the message transmitted 0011–0000.

60 As can be seen from the connection diagram, a fourth call of B₀ after the three preceding maintained connections (by the last unoccupied line of A of the same level: A₂) will be received by 1010–0010 instead of the transmitted message 0010–0000.

65 On comparing in FIG. 9 the two different levels of the first and second groups, there is seen an example of a reserve stage which simultaneously effects the balanced distribution of the grouped lines and access to four lines which for each level occupy only three contacts (for the lines B₀ having three group lines only two contacts per level).

70 It should be observed that in the above examples the number of junction circuits and the number of junctions are unnecessarily very high in relation to the possible occupation (for the eight accesses A there are in fact 16 junction circuits in the example considered).

75 In practice use will be made of the doubling or quadrupling of the accesses (as in the "Pentaconta" system), which in-

creases the number of elements of the switch only by one frame per doubling.

FIG. 11 illustrates another example of automatic route determination with 10-fold multiplying effected in accordance with the invention and more particularly intended for high capacity switches designed to comply with the requirements of heavy traffic; only part of a switch of this type is illustrated here.

The junction rods T 1-1, T 1-2, T 1-3, T 1-4, and T 2-1, T 2-2, T 2-3, T 2-4 up to T 0-1, T 0-2, T 0-3, T 0-4, which are illustrated only partly in the figure in order not to make the drawing too complicated, are the elements marking the occupation of the junction circuits.

With the exception of the rods T 0-1 to T 0-4 each junction rod controls a two-position switch C J 1-1 to C J 9-4. Each switch has the same index as its junction rod.

As can be seen in the figure, the junction rods are disposed in lines and columns, the same column being for example composed of the rods T 1-1, T 2-1 and of the following rods which are not illustrated: T 3-1, T 4-1, T 5-1, T 6-1, T 7-1, T 8-1, T 9-1, and T 0-1, that is to say those having the same second index. These rods control the connection points to which there are connected lines belonging to a subset of incoming lines and lines belonging to a subset of outgoing lines. Each of the lines of a subset is thus connected to the 10 junction circuits controlled by the 10 rods of the same second index.

To each column there are assigned different groups of incoming lines and outgoing lines, in order to effect the mixing of the lines.

The electromagnets E₁ and E₂ together determine the selection of the column, and are directly controlled by signals belonging to the message in accordance with the code below:

	E ₁	E ₂		35
1st column	0	0		
2nd column	0	1		
3rd column	1	0	(illustrated in FIG. 11)	40
4th column	1	1		

The electromagnets E'₃ E'₄ E'₅ E'₆ are energized in dependence on the signals received by the electromagnets E₁ and E₂ and by the configuration of the contacts representing materially the state of occupation of the junction circuits, thus determining the selection of the junction rod operated, E₁ and E₂ defining the column and the four electromagnets E'₃, E'₄, E'₅, E'₆ defining the line in accordance with the table below:

E' ₃	E' ₄	E' ₅	E' ₆	Line	50
0	0	0	0	1st line (rods T1)	
1	0	0	0	2nd line (rods T2)	
0	1	0	0	3rd line (rods T3)	45
1	1	0	0	4th line (rods T4)	
0	0	1	0	5th line (rods T5)	
0	0	0	1	6th line (rods T6)	
1	0	0	1	7th line (rods T7)	
1	1	0	1	8th line (rods T8)	
1	0	1	1	9th line (rods T9)	55
1	0	1	1	10th line (rods T10)	60

Thus, in the example illustrated in FIG. 11, the rod T 1-3 was designated by the message, but, as the rods T 1-3 and T 2-3 are occupied, the energization circuit is closed by the contacts controlled by E₁ and E₂ and by C J 1-3, C J 2-3, C J 3-3 and by the winding of E'₄, thus controlling the rod T 3-3.

The interruption message is communicated by the junction rod itself for its return to its inoperative position.

It is quite clear that, without other modifications than those corresponding to the different duties of certain elements of the switch described above, this device may be used directly as a concentrator, a switching point, and for other purposes. It must also be understood that the apparatus may be used with any radio connections.

We claim:

1. A switching device for performing switching operations between a first group of incoming lines and a second group of outgoing lines in response to an input signal representing in a selected code the identification of an incoming and outgoing line, which comprises:

a plurality of bistable input frames mounted for movement between first and second positions;

a first plurality of spaced contacts operatively associated with each of said bistable input frames, each of said contacts being connected to one of the incoming lines; means responsive to the input signal for selectively moving one of said bistable input frames from its first position to its second position;

a plurality of bistable output frames mounted for movement between first and second positions;

a second plurality of spaced contacts operatively associated with each of said bistable output frames, each of said contacts being connected to one of the outgoing lines; means responsive to the input signal for selectively moving one of said bistable output frames from its first position to its second position;

a plurality of bistable junction rods mounted for transverse movement relative to said bistable input and output frames between operative and inoperative positions; and means responsive to the input signal for selectively moving one of said bistable junction rods from its inoperative position to its operative position to connect a contact associated with the selected bistable input frame moved to its second position to a contact associated with the selected bistable output frame moved to its second position.

2. The switching device of claim 1, which includes:

a first support for mounting said first plurality of spaced contacts adjacent to said bistable input frames, said first support having a plurality of contact blades projecting therefrom and normally located out of engagement with said spaced contacts;

a second support for mounting said second plurality of spaced contacts adjacent to said bistable output frames, said second support having a plurality of contact blades projecting therefrom and normally located out of engagement with said spaced contacts; and

means actuated by movement of one of said bistable input frames and one of said bistable output frames to their second positions and by movement of one of said bistable junction rods to its operative position for actuating one of the contact blades on said first support and one of the contact blades on said second support to move those contact blades into engagement with the corresponding spaced contacts.

3. The switching device of claim 2, wherein the means for actuating the contact blades includes:

a first set of balls mounted on said bistable input frames, one of said balls being moved into operating relationship with one of the contact blades of said first support upon movement of its bistable input frame to its second position and movement of one of said junction rods to its operative position; and

a second set of balls mounted on said bistable output frames, one of said balls being moved into operating relationship with one of the contact blades of said second support upon movement of its bistable output frame to its second position and movement of that junction rod to its operative position.

4. A switching device for selectively operating a plurality of circuits, which comprises:

a first card for supporting the circuits, said card having a plurality of elastic blades projecting therefrom for making electrical connections to the circuits located on said card when said blades are moved into contact with the circuits; a plurality of bistable input frames mounted for transverse movement relative to said card from inoperative positions to operative positions, each of said bistable input frames having a plurality of notches formed therein;

- a first set of balls located in said notches formed in said bistable input frames;
- a plurality of selection rods mounted for transverse movement relative to said bistable input frames from first positions to second positions, each of said selection rods having a first set of slots formed therein corresponding in number to the bistable input frames, said slots being located adjacent to said notches of said bistable input frames when said selection rods are located in their first positions;
- means for selectively moving one of said bistable input frames from its inoperative position to its operative position to move the balls located in the notches formed in that bistable input frame into the slots of the selection rods located adjacent to those notches; and
- means for selectively moving one of said selection rods from its first position to its second position to move the ball located in one of its slots into an operating relationship with one of said blades to bend that blade into contact with the corresponding circuit on said card.
5. The switching device of claim 4, which includes:
- a plurality of elastic tongues located adjacent to said blades, each of said tongues being actuated by movement of one of said blades into operating relationship with one of said blades for engaging the blade to urge it into contact with the corresponding circuit on said card.
- 20
6. The switching device of claim 4, which includes:
- a plurality of bistable output frames mounted for transverse movement relative to said card from inoperative positions to operative positions, each of said bistable output frames having a plurality of notches formed therein;
- 25
- each of said selection rods having a second set of slots formed therein corresponding in number to the number of bistable output frames, said slots normally being located adjacent to said notches of the bistable output frames;
- a second set of balls located in the notches formed in said bistable output frames;
- a second card having a plurality of circuits mounted thereon and a plurality of elastic blades projecting therefrom for making electrical connections to the circuits located on said second card when said blades are moved into contact with the circuits; and
- 30
- means for selectively moving one of said bistable output frames from its inoperative position to its operative position to move the balls of said second set located in the notches formed in that bistable output frame into the slots formed in said selection rods and located adjacent to those notches, one of the balls being moved into an operating relationship with one of said blades upon movement of one of said selection rods to its operative position to bend that blade into contact with the corresponding circuit on said second card.
- 35
7. The switching device of claim 6, which includes:
- a plurality of elastic tongues located adjacent to the blades projecting from said second card, each of said tongues being actuated by movement of one of the second set of balls into operating relationship of one of said blades for bending said blades into contact with the corresponding circuit of said second card.
- 40
8. A switching device for performing switching operations between a first group of incoming lines and a second group of outgoing lines in response to an input signal representing in a selected code the identification of an incoming and outgoing line, which comprises:
- a plurality of bistable input frames mounted for movement between first and second positions;
- a first plurality of spaced contacts operatively associated with each of said bistable input frames, each of said contacts being connected to one of the incoming lines;
- 45
- a plurality of bistable output frames including first and second groups of bistable output frames, each of said output frames being mounted for movement between first and second positions;
- 50
- 55

- a second plurality of spaced contacts including (1) a first group of contacts operatively associated with each of the bistable output frames of said first group of bistable output frames, each of said contacts being connected to one of the outgoing lines and (2) a second group of contacts operatively associated with each of the bistable output frames of said second group of bistable output frames, each of said contacts being connected to one of the outgoing lines;
- 10
- a plurality of bistable junction rods including first and second groups of bistable junction rods mounted for transverse movement relative to said bistable input and output frames between operative and inoperative positions;
- 15
- means responsive to the input signal for selectively moving a bistable input frame having a contact associated with the incoming line identified by the input signal from its first position to its second position;
- means responsive to the input signal for selectively moving a bistable output frame of each group of bistable output frames having a contact associated with the outgoing line identified by the input signal from its first position to its second position;
- 20
- means responsive to the input signal for selectively moving a priority bistable junction rod of said first group of bistable junction rods from its inoperative position to its operative position to connect the contact associated with the selected bistable input frame moved to its second position to the contact associated with the selected bistable output frame of said first group of bistable output frames moved to its second position; and
- 25
- means responsive to the input signal for selecting and moving an alternate bistable junction rod of said second group of bistable junction rods from its inoperative position to its operative position in the event that said priority bistable junction rod of said first group is occupied to connect the contact associated with the selected bistable input frame moved to its second position to the contact associated with the selected bistable output frame of said second group of bistable output frames moved to its second position.
- 30
9. The switching device of claim 8, which includes:
- switching means actuated by movement of one of said bistable junction rods of said first group of bistable junction rods to its operative position and by movement of one of said bistable output frames of said second group of bistable output frames to its second position for controlling the selection of the alternate bistable junction rod of said second group of bistable junction rods when said priority bistable junction rod is occupied.
- 35
10. The switching device of claim 9, wherein said switching means includes:
- a switch actuated by movement of one of said bistable junction rods of said second group of bistable junction rods to its operative position for controlling the selection of another alternate bistable junction rod of said second group of bistable junction rods when said priority bistable junction rod and a first alternate bistable junction rod are occupied.
- 40
11. A switching device for performing switching operations between a first group of incoming lines and a second group of outgoing lines in response to an input signal representing in a selected code the identification of an incoming and outgoing line which comprises:
- a plurality of bistable input frames mounted for movement between first and second positions;
- a first plurality of spaced contacts operatively associated with each of said bistable input frames, said contacts being arranged in first and second levels and each of said contacts being connected to one of the incoming lines;
- 45
- a plurality of bistable output frames including first and second groups of bistable output frames, each of said output frames being mounted for movement between first and second positions;
- 50
- 55

a second plurality of spaced contacts including (1) a first group of contacts operatively associated with each of the bistable output frames of said first group of bistable output frames, said contacts being arranged in said first and second levels and both levels including contacts connected to each of the outgoing lines, and (2) a second group of contacts operatively associated with each of the bistable output frames of said second group of bistable output frames, said contacts being arranged in said first and second levels and both levels including contacts connected to each of the outgoing lines; 10

a plurality of bistable junction rods including (1) first and second groups of bistable junction rods located in said first level and mounted for transverse movement relative to said bistable input and output frames between operative and inoperative positions, and (2) third and fourth groups of bistable junction rods located in said second level and mounted for transverse movement relative to said bistable input and output frames between operative and inoperative positions; 15

means responsive to the input signal for selectively moving a bistable input frame having a contact associated with the incoming line identified by the input signal from its first position to its second position; 20

means responsive to the input signal for selectively moving a bistable output frame of each group of bistable output frames having a contact associated with the outgoing line identified by the input signal from its first position to its second position; 25

means responsive to the input signal for selecting and moving a priority bistable junction rod of said first group or said third group of junction rods from its inoperative position to its operative position to connect the contact as- 30

sociated with the selected bistable input frame to the contact associated with the selected bistable output frame of said first group of said bistable frames; and
means responsive to the input signal for selecting and moving an alternate bistable junction rod of said second group or said fourth group of bistable junction rods from its inoperative position to its operative position in the event that said priority bistable junction rod of said first group of said third group is occupied to connect the contact associated with the selected bistable input frame to the contact associated with the selected bistable output frame of said second group of bistable output frames.

12. The switching device of claim 11, which includes:
switching means actuated by movement of a priority bistable junction rod of said first group or said third group of bistable junction rods to its operative position and by movement of one of said bistable output frames of said second group of bistable output frames to its second position for controlling the selection of the alternate bistable junction rod of said second group or said fourth group of bistable junction rods when said priority bistable junction rod is occupied.

13. The switching device of claim 12, wherein said switching means includes:

a switch actuated by movement of the alternate bistable junction rod of said second group or said fourth group of bistable junction rods to its operative position for controlling the selection of another alternate bistable junction rod of said second group or said fourth group of bistable junction rods when said priority bistable junction rod and a first alternate bistable junction rod are occupied.
